UNITED STATES PATENT OFFICE.

ARTHUR G. WIEDMANN, OF KANSAS CITY, MISSOURI.

STEIN.

1,344,072.

Specification of Letters Patent. Patented June 22, 1920.

Application filed October 7, 1914. Serial No. 865,410.

To all whom it may concern:

Be it known that I, ARTHUR G. WIEDMANN, a citizen of the United States, residing in Kansas City, in the county of Jackson and State of Missouri, have invented a new and useful Improvement in Steins, of which the following is a specification.

My invention relates in general to steins and has for its principal object the provision of a cheap and attractive stein which may be used for the packaging and selling of cigars, the purpose being to pack the cigars in the stein and to give to each purchaser of a full package of cigars the stein 15 in which the cigars are contained.

It is therefore a principal object of this invention to construct a stein of cheap materials so put together as to give an imitation of earthenware or crockery so that the 20 stein may be used for the drinking of beer and the like or to form an attractive ornament in a dining room or den.

A principal object of this invention is to provide a stein which while having all of 25 the appearance of a well designed and attractive earthen-ware article, will be made largely of tin or other appropriate sheet metal.

A further object of the invention is the 30 construction of such an article of relatively frail material which will be strong and durable and not likely to be damaged with ordinary handling and use.

Other objects and advantages of the invention will be apparent as it is better understood from the following description when considered in connection with the accompanying drawing illustrating a preferred embodiment thereof.

40 Referring to the drawing,

Figure 1 is a perspective view of a stein adapted for the packaging of cigars and embodying my invention; and Fig. 2 is a central, transverse, vertical section of the 45 same.

The stein embodying my invention and shown on the drawing consists of the sheet metal parts 3, 4, 5 and 6, the part 3 being the cylindrical wall of the body, the part 4 50 the bottom of the body, the part 5 the handle of the stein and the part 6 the cover.

The cylindrical part 3 consists of a single sheet of tin or other material bent to cylindrical form and having its longitudinal edges secured together throughout their 55 length at 7. The bottom is secured in place

in any suitable fashion, being shown in the present instance as connected to the cylindrical side wall by the interlocking seam 8. The handle 5 extends from the bottom of the 60 stein substantially to the top and is interlocking connected at 9 between the bottom and the adjacent edge of its cylindrical side 3. At the top a pair of lips 10 are provided which are inserted through suitable apertures in the side wall and bent down as shown in Fig. 2. The handle 5 is given an attractive curve and is located so that the seam 7 between the adjacent longitudinal edges of the cylindrical side wall is 70 substantially hidden by the handle. The upper portion of the handle is disposed substantially horizontally and is cut away centrally at 11 to provide a pair of lips 12 which are bent upwardly into substantial 75 parallelism, and these lips are provided with aligned apertures 13 for the receipt of a pivot pin 14 which, as will be later explained, pivotally connects the cover to the handle. The upper edge of the side wall is 80 bent outwardly and back upon itself to provide a false wire bead or edge 15 which stiffens the structure and provides a surface against which the cover 6 may be closed.

The cover 6 is curved throughout its central part spherically and is bent first upwardly at 16 and thence downwardly at 17 to provide a rest and curved edge adapted to engage over the false wire or bead edge 15 of the side wall. The cover is also provided with a projection 18 extending rearwardly and outwardly above the handle and the side edges 19 of this projection are bent downwardly into substantial parallelism and fit between the upwardly extending lips 95 12 of the handle. The pivot pin 14 passes through suitable apertures in these wings to pivotally connect the cover in place. The projection 18 extends rearwardly of the pivot 14 to provide a thumb-piece 20 which 100 may be pressed to lift the cover in the manner ordinarily employed in lifting the cover of an earthen-ware stein.

The stein is given a surfacing 21 of suitable material imitating earthen-ware which 105 may be applied in any desired fashion. This surface is rough, as will be noted from viewing Fig. 1, and may be provided by lithographing, printing or otherwise applying a coat of material which will produce 110 the effect desired. Earthen-ware itself or a fine cement may be used. Indeed numerous

substances are believed to be available for this purpose. The effect of an earthen-ware or ceramic article is further produced by embossing the design, as seen at 22 in Fig. 5 2, the embossing with the surfacing creating the impression on the eye of a molded earthen-ware article.

It will be obvious that a stein constructed as described will be strong and durable by 10 reason of the efficient connections between the various parts, and by reason also of the diameter or spherical shape given the cover, the convexity of the outer surface reducing materially the danger of denting. Where 15 the cover is opened by pressing upon the thumb-piece 20, this thumb-piece may pass downwardly through the aperture 11 to permit the cover to fall completely back out of the way of the person desiring to drink 20 from the stein. The diameter of the article is preferably such that it may contain a commercial package of cigars, the intention being to give each purchaser that buys a complete commercial package of cigars or 25 other contents the stein described.

It will be obvious that various changes may be made in the form of the article and arrangement of its parts and the method and materials used in its construction without departing from the spirit and scope of 30 my invention or sacrificing any of its material advantages, the form hereinbefore

described being merely a preferred embodiment thereof.

I claim:

1. A package for cigars and other purposes, comprising a sheet metal body having a beaded cylindrical edge around its mouth; a sheet metal cover having a dome-shaped center and an upstanding bent edge embracing within and without said beaded edge of the body and having an integral extended thumb-piece; an outwardly extended handle united with the body; and a hinge pin pivotally connecting said thumb-piece 45 with the handle.

2. A package for cigars and other purposes, comprising a sheet metal body; a sheet metal outstanding handle united with said body and having at its sides integral upstanding lips formed by cutting out and bending up a middle portion of the handle; a cover fitting the mouth of said body and formed with an outstanding thumb piece extending over and deppressible into the cut-out part of the handle and formed with depending side edges parallel with said lips of the handle; and a pivot pin connecting said lips with said side edges of the thumb-piece.

ARTHUR G. WIEDMANN.
